UNITED STATES PATENT OFFICE

JOHN FERGUSON, OF POLLOKSHIELDS, GLASGOW, SCOTLAND

APPARATUS FOR USE IN OIL AND LIKE WELLS

Application filed April 13, 1929, Serial No. 354,901, and in Great Britain April 17, 1928.

This invention comprises an improved apparatus for use in oil wells and the like.

In oil wells it is customary to first sink a cylindrical casing of large diameter, there-
5 after sink a casing of slightly smaller di-
ameter which extends from the ground level
to a greater depth than the first, and in like
manner sink other casings, each succeeding
one being of less diameter than the former
10 and extending from the ground level to a
greater depth.

It will thus be apparent that parts of the
well are formed of several concentric cas-
ings and while it is desirable to so reinforce
15 the well to a certain extent, it is customary
to remove what may be regarded as superflu-
ous casing.

That is the portion of certain of the inner
20 casings is cut away at a level just above the
foot of the enclosing casings, the portion of
the cut casings above said level being then
removed.

My invention has for its object to provide
25 improvements whereby the casings can be
more easily and expeditiously cut than for-
merly.

My invention has for its object to provide
an improved tool for the purpose set forth
30 wherein the various operations can all be
effected automatically on power being trans-
mitted to the tool within the well.

My invention has further for its object to
provide an improved means for supporting
35 and transmitting power to the tool.

In order that my invention will be proper-
ly understood I have hereunto appended ex-
planatory sheets of drawings whereon:-

Figure 1 illustrates diagrammatically a
40 preferred construction of apparatus in ac-
cordance with my invention, part of the
length of the driving shaft and part of the
line of enclosing tubing being shown broken
away.

Figure 2 is a somewhat similar view to that
45 shown in Figure 1, but showing certain parts
in section and to a larger scale.

Figure 3 is an end elevation of the upper
50 part of the apparatus showing the pawl and
ratchet mechanism for imparting a slow ro-
tary movement to the line of tubing.

Figure 4 illustrates an end elevation of the
mechanism for feeding forward the cutter
or saw.

Figure 5 illustrates a section through the
55 upper part of the apparatus to a larger scale
and also showing a portion of the line of
shafting and enclosing tubing.

Figure 6 shows in section to a larger scale
the tool holder and the means for feeding
60 forward the cutter or saw the latter also
being shown.

Figure 7 is an end elevation of Figure 6
looking from the left and Figure 8 is a sec-
tional plan view on the line 8—8 of Figure
6, the cutter or saw being omitted.

Figure 9 shows the preferred means by
which the speed of rotation of the cutter or
saw about the longitudinal centre of the ap-
65 paratus can be varied.

Figure 10 is a sectional end elevation of
Figure 9 looking to the left.

Figure 11 illustrates a portion of the
ratchet wheel and clutch by which it can be
70 quickly brought into and out of operation.

Figure 12 is a fragment of the ratchet wheel
75 showing a pair of co-operating pawls.

Referring to the drawings:-

1 designates an outer casing and 2 an in-
80 ner casing of a well, 3 is the rotary cutter or
saw, 4 is the inner line of shafting and 5 is
an outer line of tubing enclosing the shaft-
ing 4.

The line of shafting 4 is formed of an inter-
85 connected series of relatively short lengths,
each length, at one end thereof, being squared
as at 4^a, while the other end of each length
is enlarged and correspondingly recessed as
at 4^b to receive the squared end of an inter-
fitting length, see Figure 5. The top length
90 of said line of shafting receives the squared
end of a spindle 6 to which is keyed a bevel
wheel 7 in mesh with a bevel wheel 8 keyed
to a short spindle 9. The latter is jour-
nalled in bearings 10 carried by a pedestal 11.

One end of the spindle 9 is connected by
means of a universal joint to one end of a
95 telescopic connecting rod 12 which latter is
connected in like manner to the shaft 13
which carries the fast and loose pulleys 14 and
14^a. The other end of the spindle 9 trans-

mits the necessary motion to the enclosing line of tubing as will be subsequently described.

The enclosing line of tubing is likewise formed of a series of relatively short lengths which are rigidly coupled together by screw coupling pieces 5^b.

The upper end of the tubing has secured thereon by means of a pinch screw 16^a a worm wheel 15 which is mounted to rotate on the base 16 supporting the pedestal 11, ball bearings or other anti-friction bearings being introduced between the said wheel and base.

The upper end of each length of tubing carries a ball race 5^a or washer on which rests the shoulder formed by the squared end 4^b of the length of shafting enclosed thereby. Thus each length of shafting is freely supported by its length of enclosing tubing.

Near the lower end of the line of shafting and line of enclosing tubing is a guide 17 formed of a frame carried by collars 18 free on the line of enclosing tubing and provided with a series of spring arms 19 having contact pieces 19^a which bear on and grip the casing to be cut. Immediately below this guide and secured to and forming part of the line of tubing is a cylindrical casing 20 to the lower end of which is screwed or otherwise secured a vertically slotted cylinder 21. This cylinder, in addition to being slotted vertically, is provided with three transverse slots 22, 23 and 24. A sliding member 25 which constitutes a tool holder, carries the rotary cutter or saw 3, and is accommodated in the centre slot 23, the cutter or saw being operatively connected by means of a universal joint to the one end of a telescopic connecting rod 26 the other end of which is connected in like manner to the lower end of the line of shafting 4. Located in the cylinder 20 and connecting the two lowest lengths of the shafting is reducing gear carried in the gear box 27.

It will therefore be apparent that on the fixed pulley being driven the line of shafting 4 is driven through the connecting rod 12, spindle 9 and bevel gearing 8 and 7, and said shafting transmits its motion through said speed reducing gear located in the gear box 27 and connecting rod 26 to rotate the cutter or saw 3 about its own axis.

The said spindle 9 transmits through an eccentric device and connecting rod 28 a reciprocating movement to a cross head 29 which travels on the guide rods 30 and which carries the two rods 31. These rods, at their lower ends, are provided with pawls which engage with a ratchet wheel 32 mounted on the shaft 33 of a worm 33^a which meshes with the worm wheel 15. Said worm shaft 33 is journalled in a casing 33^b cast integral with the base 16 of the pedestal.

It will therefore be seen that simultaneously with the rotation of the line of shaft-

ing 4 the line of tubing 5 is slowly rotated from the spindle 9 by means of the said pawl and ratchet mechanism and worm and worm wheel, the line of tubing being connected to said worm wheel.

As the slotted cylinder 21 is secured to the end of the line of tubing and as said cylinder carries the tool holder 25 it follows that the cutter or saw 3, while being rotated about its own axis by means of the line of shafting 4, is also rotated, but much more slowly, about the longitudinal centre of the apparatus.

The means for effecting the radial feed of the tool will now be described.

Guides 22^a and 24^a, each having a rectangular opening therein, are fitted into the slots 22 and 24 formed in the cylinder 21 and are fixed in position by the transverse bolts 22^b and 24^b, see particularly Figures 6, 7 and 8.

A vertical bar 35, rectangular in cross section and provided with a slot 35^a in the form of a quadrant, is fitted within the holes in said guides 22^a and 24^a and also passes through a vertical slot formed in the sliding member or tool holder 25.

A screw threaded spindle 36 is threaded through a corresponding internally threaded nut 37 secured to the lower end of said bar 35.

Said spindle does not rotate but is secured to a guide formed by a frame 38 having spring arms 39 provided with contact pieces 39^a which grip the side of the casing being cut.

Therefore, while the cutter or saw 3 is being simultaneously rotated about its own axis and about that of the centre of the apparatus, the internally threaded nut 37 is being slowly rotated on the screwed spindle 36 which latter is held stationary. Consequently said nut travels vertically on the screw threaded spindle and imparts a like movement to the vertical bar 35. A cross pin 23^b carried by the tool holder engages with the quadrant shape slot 35^a and the latter, acting like an inclined plane, imparts a radial feed movement to the tool holder, and therefore to the cutter or saw carried thereby. The shape of said slot is such that after the cutting operation is effected the cutter is automatically withdrawn to a non-operative position. By providing screw threaded spindles 36 with threads of varying pitch and correspondingly internally threaded nuts 37, the rate of the radial feed of the cutter or saw can be regulated.

The preferred means by which the speed of rotation of the rotary cutter or saw about the longitudinal centre of the apparatus is controlled is shown in Figures 9 and 10.

Secured on the end of the spindle 9 is a disc 9^a provided with an elongated slot 9^b within which is fitted a screw spindle 9^c and an internally screw threaded sleeve 9^d screwed thereon. Said sleeve carries an outwardly

projecting stud 9^e to which is connected the upper end of the connecting rod 28.

Said screw threaded spindle is prevented from moving longitudinally by means of a pin 9^f passing through a hole in the disc and a groove in the head of the spindle, but it can be rotated and for that purpose may be provided with a tommy hole.

By rotating the said spindle the position of the sleeve 9^d can be adjusted thereon and therefore the eccentricity of the centre of the stud 9^e with respect to the centre line of the spindle 9 can be regulated. As the degree of eccentricity controls the amount of travel of the reciprocating cross head 29 and the travel of the pawls, the speed of rotation of ratchet wheel and worm wheel, the line of tubing and the tool holder can be regulated so that the circumferential travel of the cutter or saw about the longitudinal centre line of the apparatus can be regulated to suit any diameter of casing being cut.

In order to impart a very steady rotary movement to the tool holder I provide two pairs of pawls, one pair pulling round the ratchet wheel when the cross head moves upwards and the other pair pushing round the ratchet wheel when the cross head moves downwards so that a small movement is imparted to the ratchet wheel on both the up and down strokes of the cross head, thereby ensuring a steady continuous rotary movement of the line of tubing, which, in turn, ensures a steady and constant circumferential and radial feed motion being imparted to the cutter or saw.

Where a rotary movement is imparted to a ratchet wheel by means of a cooperating reciprocating pawl such movement must be a step by step movement.

By the provision of the pawls pulling alternately upwardly and downwardly at the opposite sides of the wheel, a substantial continuous movement is imparted to the ratchet wheel and thereafter to the wheel.

A pair of pawls 41 and 41^a are shown in Figure 12 and from which it will be seen that while one of the pawls is in engagement with a tooth of the ratchet wheel the other is not. By such provision the amount of lost movement which would occur should a pawl be on the top of a tooth at the end of its idle movement is reduced by half and this permits of fine adjustment of the speed of rotation of the ratchet wheel.

Said pawls are carried between two plates 42 provided with inwardly projecting curved ribs 43 which fit within corresponding annular grooves in the ratchet wheel, the operating ribs and grooves serving as a guide for the pawls.

The ratchet wheel is secured on the tapered end of the shaft 33 by means of a wing nut 44. By slackening said nut the ratchet wheel can be allowed to rotate independently of

the said shaft so that no rotary movement is imparted to the latter and consequently no movement imparted to the line of tubing and tool holder, the plates carrying the cutter or saw then rotating only about its own axis.

In cutting casings it is necessary that the cutter or saw should be so positioned that it will commence to cut almost immediately after the feed forward movement commences and consequently provision must be made for this in cutting casings of various diameters.

In Figure 6 the tool holder is shown provided with three transverse holes through either of which the pin 23^b can be passed and by this the position of the tool adjusted within the limits governed by the distance said holes are apart.

The cutter or saw is not directly mounted on the tool holder but is carried by a bracket or block 45 which fits within a slot formed in the end of the tool holder and is held therein by means of a clamping plate 45^a and bolt and nut 46 and 46^a.

By adjusting the tool holder and by the provision of thin packing strips 47 inserted between the rear end of the block and end of the slot in the tool holder adjustment can be made to suit any diameter of casing to be cut.

It will be understood that adjustment can also be effected by the use of sliding tool holders of various sizes and in combination with such packing strips.

In use a spindle 36 with corresponding nut is selected to give the desired rate of radial feed to the cutter or saw and is fitted to the foot of the slotted cylinder 21.

The cutter or saw is adjusted by means of the tool holder and packing strips so that it will commence to cut almost immediately after the radial feed motion commences.

The shafting 4 and enclosing tubing 5 are adjusted to the required length and supported centrally within the well by the base 16 of the pedestal and by the two guides carried by the said tubing near the lower end thereof and bearing on the inner wall of the casing to be cut, i. e., the casing 2.

On the fixed pulley being rotated the cutter or saw is rotated about its own axis by means of the line of shafting 4 and is simultaneously rotated bodily in a circular path about the longitudinal centre of the apparatus, or casing being cut, but at a relatively very slow speed, by means of the line of tubing.

Also simultaneously with the said two movements the cutter or saw is fed slowly outwards by means of the screw and nut feed device and the inclined plane action of the slot 35^a. The cutter or saw therefore travels round and cuts into the casing 2 while rotating about its own axis, such operations

being continued until the said casing is completely cut through.

The superfluous casing can then be removed and the apparatus used to effect further like operations.

Should it be desired to quickly or temporarily stop the circumferential rotation of the cutter or saw about the longitudinal centre of the apparatus, this can be quickly done by merely slackening the wing nut 44 as explained above, and should it be desired to alter the rate of such circumferential movement, this can be done by rotating the screwed spindle 9.

15 The slots 35^a in the bar 35 may be designed, as shown, so that it imparts a quick initial movement to the tool holder, thereafter a much slower movement, and, when the cutting operation is completed automatically effects a quick return movement without stopping or altering the direction of the drive.

The line of tubing formed of rigidly interconnected lengths of tubes forms a rigid support for the tool while the short lengths of independently supported shafting enables the tool when located at considerable depths to be operated from the surface. Each length of tubing and shafting is conveniently about 22 feet.

20 What I claim is:—

1. An apparatus for the purpose set forth comprising a rotary cutter or saw, a holder for said cutter or saw, an inner line of shafting to rotate said cutter or saw about its own axis, a rotatably mounted line of tubing enclosing said shafting and by which the holder together with the cutter or saw is supported and rotated, a guide member to grip the inner wall of the tube being cut and means to feed the saw or cutter outwards comprising a non-rotatable screw carried by said guide member, a nut to travel on said screw, a vertically sliding member having a longitudinal slot and operatively connected to the nut and a transverse pin carried by the holder and engaging said slot, the said sliding member effecting the forward feed of the saw or cutter.

2. An apparatus of the stated character comprising a rotary cutter, a holder for said cutter, an inner shaft arranged to rotate the cutter about its own axis, a rotatably mounted tube enclosing said shafting and by which the holder carrying the cutter is supported, means for rotating said tubular casing with said holder, a guide suspended by the tubular casing and arranged to engage the tube to be cut, and means for feeding the cutter radially outwards and comprising a nut and screw, one of which is rotated by the holder and the other thereof held by said guide.

3. An apparatus for the purpose set forth comprising a rotary cutter or saw, a holder for said cutter or saw, an inner line of shafting to rotate said cutter or saw about its own

axis, a rotatably mounted line of tubing enclosing said shafting and by which the holder of the cutter or saw is supported and rotated, a guide member to grip the inner wall of the tube being cut, and means to feed the cutter or saw outwards comprising a non-rotatable screw carried by said guide member, a nut to travel on said screw, a vertically sliding member having a curved slot and operatively connected to the nut, and a pin carried by the tool holder and engaging the slot, the said nut and screw in combination with the pin and curved slot effecting a quick initial feed movement, thereafter a slow feed movement and a quick final return movement.

4. An apparatus of the stated character comprising a rotary disc cutter or saw, a support, a holder slidably mounted on said support and carrying said cutter or saw, a line of shafting to rotate the cutter or saw about its own axis, a line of tubing to rotate said support together with the holder and the cutter or saw, a driving member, gearing by which both the line of shafting and the line of tubing are simultaneously rotated by said driving member, a stationary member suspended by the line of tubing but not rotating therewith, and a member mounted to rotate with the holder and cooperating with the stationary member by which the cutter or saw is fed outwards.

5. An apparatus for the purpose set forth comprising a rotary cutter, a holder therefor, a support for said holder, an inner line of shafting to rotate said cutter about its own axis, a rotatably mounted line of tubing enclosing said shafting and by which the support and holder carrying the cutter is supported, a driving member to rotate said line of shafting, means to rotate the line of tubing also driven by said member and comprising a ratchet wheel operatively connected to the line of tubing, a rod reciprocated by the driving member, a housing carried by said rod and engaging with the ratchet wheel so as to travel circumferentially thereon, at least one pawl carried by said housing and arranged to engage with the teeth of the ratchet wheel when moved in one direction and to over-ride the teeth when moved in the other direction and means for varying the stroke of said rod to vary the rate of travel of the support with cutter about the longitudinal axis of the apparatus with respect to the rotation of the cutter or saw about its own axis.

6. An apparatus for the purpose set forth comprising a rotary cutter, a holder therefor, a support for said holder, an inner line of shafting to rotate said cutter about its own axis, a rotatably mounted line of tubing enclosing said shafting and by which the support and holder carrying the cutter is supported, a driving member to rotate said line of shafting, means to rotate the line of tubing

also driven by said member and comprising a ratchet wheel operatively connected to the line of tubing, an eccentric driven by the driving member, a reciprocating member 5 connected to said eccentric, means to vary the degree of eccentricity of the eccentric and therefore the stroke of the reciprocating member, a housing carried by said member and engaging with the ratchet wheel so as 10 to travel circumferentially thereon, and at least one pawl carried by the housing and arranged to engage with the teeth of the ratchet wheel when travelling in one direction and to over-ride the teeth when travelling in the 15 other direction.
